UNITED STATES PATENT OFFICE.

HOWARD J. WEBSTER, OF PHILADELPHIA, PENNSYLVANIA.

BEARING BAR FOR FURNACE GRATE BARS.

Application filed August 3, 1925. Serial No. 47,783.

This invention relates to bearing bars used to support furnace grate bars in the fire chambers of a steam boiler furnace and is more particularly designed to support 5 grate bars of the construction shown in my U. S. Patent Number 1,527,940, dated February 24, 1925, in connection with a steam boiler furnace, as illustrated in my U. S. Patent Number 1,545,715, dated July 14, 10 1925.

The objects of the invention are:

First, to construct bearing bars of the character referred to which is capable of being readily, cheaply and quickly built into 15 the front, back, or other walls of a fire chamber of steam boiler furnaces and which will prevent the by-passing or leakage of the high-pressure air usually used in the combustion of the grade of coal used in 20 connection with the grate bars employed.

Second, to so construct the bearing bars with means for supporting the ends of the 25 grate bars, that the lodgement or accumulation of ashes at the ends of the grate bars is prevented and permits the ready and 30 easy slicing of the fire at all times.

Third, to construct a bearing bar for the support of grate bars which is capable of 35 being employed at the front or back wall or intermediate of said walls of a fire chamber, and at the same time prevent the passage of a high-pressure air used or the accumulation or lodgment of ashes at the 40 sections of the bearing bars on which the grate bars are adjacent or resting upon.

Fourth, other objects and advantages of 45 the invention will appear from the detailed construction and arrangement of parts and mode of operation to be hereinafter given.

The invention consists of structural characteristics and relative arrangements of elements or parts to be more fully described and particularly pointed out in the appended claims.

In the drawings, in which similar reference characters indicate the same parts in 50 the several figures:

Figure 1 is a fragmentary longitudinal section of a fire chamber of a steam boiler 55 furnace equipped with the bearing bars.

Figure 2 is an enlarged top plan view of a section of the grate bed showing the bearing bars and manner of supporting the grate bars.

Figure 3 is a perspective and fragmentary view of one of the bearing bars employed

at an intermediate point between the front and back walls of the fire chamber, and

Figure 4 is a similar view as Figure 3 of a bearing bar employed at the front or back 60 wall of the fire chamber.

Referring to the drawings, 10 is the usual front wall and 11 the back or rear wall of a fire chamber 12 of a steam boiler furnace, 13 is the fuel door for feeding fuel to the 65 grate bars 14, 14, supported above the ash pit 15 having the door 16.

The improved front and back bearing bars 17 and 18 are embedded and supported from the side or front and back walls 10 70 and 11, as indicated, and preferably comprise, as shown in Figure 4, a flat bar section 19 extending transversely of the fire chamber 12, as shown in Figure 2, and having one of its edges provided with a series 75 of preferably equally spaced and alternating projections 20, 20, and indentations 21, 21, for purposes to be presently described.

The grate bars 14, 14, for which the bearing bars 17 and 18 are particularly designed 80 are of the construction shown and described in my former U. S. Patent Number 1,527,940, and need no further disclosure and are supported with their ends resting on said bearing bars 17 and 18, as shown in Figures 85 1 and 2, and said sections of grate bars are arranged side by side, as shown in said patent and indicated by dotted lines in Figure 2.

When the grate surface is to be enlarged 90 or extended, an intermediate bearing bar 22 may be employed, as shown in Figures 1 and 2, and preferably of T-shape in cross section, as shown in Figure 3, and consisting of a flat bar 23 having each of its edges 95 provided with a series of spaced and alternating projections 24, 24, and indentations 25, 25, similarly to and duplicate of those shown in Figure 4, said projections 24, 24, and indentations 25, 25, of the intermediate 100 bearing bar 22, are oppositely disposed on the two edges of the bar, as clearly illustrated in Figure 3, and said bar 22 has formed integrally with it on its bottom face a depending flange 26 normal to the plane 105 of said face.

The bearing bars 17, 18 and 22 being arranged as shown and described and the plurality of grate bars 14, 14, being disposed to entirely separate and divide the fire chamber 12 from the ash pit 15, when forced draft 110 or high air pressure is created in said ash pit

15 and below the grate bars on which a bed of smaller sizes of anthracite, or other low grade fuel has been disposed, the said bearing bars 17, 18, and 22 are arranged and in 5 close sealing contact only with the under portions of the extreme ends of all the grate bars, as shown in Figure 2, to prevent leakage of the forced draft or high pressure air at these points, and said air pressure is compelled to pass through the fuel bed in a 10 constant and uniform manner, thereby insuring an even, proper and efficient combustion of the fuel over the entire fuel bed or grate surface, more especially at the end sections 15 of the several grate bars 14, 14, directly over the improved bearing bars 17, 18, and 22, for the reason that the said bearing bars are provided with the cut out portions or indentations 21, and 25, which permit the ashes to 20 fall through the slits or openings in the grate bars directly into the ash pit without lodgement or contact with said bearing bars. Said bearing bars 17, 18, and 22 also allow for the usual contraction and expansion of 25 the grate bars 14, 14, without breaking the sealing contact between said bearing bars and grate bars.

From the foregoing description of the construction and arrangement of the elements of the bearing bars and mode of operation, it will be readily understood a grate bar supporting means has been devised which comprises a minimum number of simple elements, capable of being cheaply manufactured and readily installed and renewed without the use of skilled labor.

It will also be seen that all the objects and advantages recited in the statement of invention have been fully carried out, and 40 while the preferred form has been shown and described, it is to be understood that changes will suggest themselves without in any way modifying the material features of construction or departing from the spirit of 45 the invention, as expressed in the claims.

What I claim is:

1. A bearing bar for furnace grate bars having a series of separated draft openings arranged transversely of the longitudinal 50 axes of said grate bars comprising a bar hav-

ing a top plane surface and an edge provided with a series of separated and alternating projections and indentations, the top surface of said bar adjacent to the outline of said projections and indentations so constructed, arranged and adapted to intimately contact with and support the ends of grate bars placed on said bearing bar and not intercept ashes dropping through the openings at the ends of said grate bars.

2. A bearing bar for furnace grate bars having a series of separated draft openings arranged transversely of the longitudinal axes of said grate bars comprising a straight bar having a top plane surface and two parallel straight edges, one of said edges provided with a series of separated and alternating projections and indentations, the top surface of said bar adjacent to the outline of said projections and indentations so constructed, arranged and adapted to intimately contact with and support the ends of grate bars placed on said bearing bar and not intercept ashes dropping through the openings at the ends of said grate bars and the other edge adapted to be embedded in or attached to a wall of a fire chamber of a furnace.

3. A bearing bar for furnace grate bars having a series of separated draft openings arranged transversely of the longitudinal axes of said grate bars comprising a straight bar T-shaped in cross section and having a top plane surface and two parallel straight edges, each of said edges provided with a series of separated and alternating projections and indentations and arranged with the projections and indentations of one edge being respectively opposite the projections and indentations of the other edge, and the top plane surface adjacent to the outlines of said projections and indentations so constructed, arranged and adapted to intimately contact with and support the ends of grate bars placed on said bearing bar and not intercept ashes dropping through the openings at the ends of said grate bars.

In testimony whereof I hereunto affix my signature.

HOWARD J. WEBSTER.
